UNITED STATES PATENT OFFICE.

JOHN JOHNSON, OF HAZELDELL, PENNSYLVANIA.

RAILWAY SAFETY DEVICE.

1,087,773.

Specification of Letters Patent. Patented Feb. 17, 1914.

Application filed April 22, 1913. Serial No. 762,860.

To all whom it may concern:

Be it known that I, JOHN JOHNSON, a citizen of the United States, residing at HazeldeLL, in the county of Lawrence and State of Pennsylvania, have invented new and useful Improvements in Railway Safety Devices, of which the following is a specification.

The present invention relates to improvements in means for preventing the wheels of rolling stock, such as railway coaches, from jumping the tracks as well as the provision of means whereby the device may be raised above the rails when the coach or vehicle enters frogs, and under other conditions.

Broadly, the improvement resides in the construction, combination and operative arrangement of parts set forth in the following specification and falling within the scope of the appended claims.

In the drawings there is illustrated a satisfactory reduction of my improvement to practice, the nature of the improvement, however, renders the important instrumentalities thereof susceptible to various forms of construction, all of which, however, fall within the scope of the appended claims.

In the drawings:—Figure 1 is a vertical longitudinal sectional view taken through the improvement, and showing the same engaging with a rail. Fig. 2 is a similar sectional view for illustrating the device out of engagement with the rail and raised above the rail. Fig. 3 is an enlarged sectional view upon the line 3—3 of Fig. 1. Fig. 4 is an enlarged sectional view taken through the valve. Fig. 5 is a vertical transverse sectional view through a modified form of the device, and illustrating by dotted lines the engaging members forced away from the rail. Fig. 6 is a similar section but illustrating the device raised above the rail. Fig. 7 is a sectional view upon the line x—x of Fig. 5. Fig. 8 is a detail section through the arms 13 and 14 and illustrating the elongated slots in the fingers 17 which receive the pointed end of the piston rod 23.

Referring now to the drawings in detail the numeral 1 designates an ordinary rail-way rail, and 2 a portion of a coach or other vehicle whose wheels are adapted to travel upon the rail.

Secured to the underframe of the vehicle 2, directly above the track 1, and through the medium of depending bracket members 3 is a casing 4. This casing embodies a

closed top and an open bottom, the said bottom having its edge turned to provide an annular bead 5. Arranged within the cylindrical casing 4 is a flanged top portion 6 of a cylinder 7, the bead 5 of the casing 4, and the flange 6 of the cylinder 7 adapted to serve as stop members for preventing the removal of the cylinder from the casing. The body of the cylinder may be frictionally engaged by the inner face of the annular bead 5, while the flanged body 6 may like-wise engage with the inner wheel of the cylindrical casing 4. The frictional contact of these members, however, not being sufficient to interfere with the free movement of the cylinder within the casing, but such an arrangement serves to retain the cylinder against wobbling and in proper position with relation to the casing and to the parts attached to the cylinder.

Interposed between the top wall of the cylinder 7 and the inner top wall of the casing 4 is a buffer 8 which is illustrated in the form of a helical spring. This spring is adapted to exert only sufficient tensioning to retain the flange 6 in a proper position within the casing 4, and does not force the said flange against the bead 5.

The cylinder 7 is formed with both a closed top and bottom, and the said cylinder, at its bottom, which may be designated by the numeral 9 has secured thereto, or may be integrally formed with two diametrically opposite plates or bracket members 10 each of which being provided with a registering opening 11, through which passes a pintle 12 which connects two curved or arcuate arms 13 and 14 respectively. It is to be understood that the plates or brackets 10 are arranged a suitable distance above the top of the rail 1, and the arms 13 and 14 are of a sufficient length to have their ends terminate below the head of the rail when the said arms are in the position illustrated in the figure of the drawings. The arms adjacent their ends are each provided with an inturned axle 15 upon each of which is mounted a substantially cone-shaped guide wheel 16, and these guide wheels are adapted to be arranged directly below the ball or head of the rail to the opposite sides of the said rail. The arms 13 and 14 have their inner faces provided each with an inwardly extending finger 17, the finger of the arm 13 being adapted to underlie the finger of the arm 14, and the said fingers are disposed a

suitable distance above the top or tread of the rail 1. The ends of these fingers 17 project a suitable distance beyond the center of the rail 1, so that the end of the finger of 5 the arm 13 extends below the end of the finger of arm 14. These finger ends are provided each with an elongated slot 18 when the device is in the position shown in Fig. 1, the purpose of which arrangement will presently be described.

Pivots connected, to one of each of the arms 13 and 14, and adjacent the hinged connections of the said arms are links 19 and 20, and the free ends of these links are 10 pivots connected as at 21.

Arranged within the cylinder 7 is a piston head 22 that is provided with a piston rod 23 that extends through suitable packing in the lower or bottom wall of a cylinder. 20 The rod 23 is connected as at 24 to the pivot 21 which connects the links 19 and 20, and the portion of the rod extending beyond the said pivot is preferably pointed as indicated by the numeral 25, and said pointed end is 25 adapted to be received within the slots 18 of the fingers 17 of the arms 13 and 14 when the device is in locked position and in engagement with the rail.

Suitably located within the cab of the engine to which the device is attached is a 30 valve 26 which at all times communicates with a branch 27 from the main air pipe of the train line. The valve 26 is provided with two curved passages 28 and 29 respectively, and the valve casing is formed with right angularly arranged ports four 35 in number and described by numerals 30, 31, 32 and 33 respectively. The pipe 27 connects with the port 30, while connected with 40 the port 31 is a flexible pipe 34 which enters the cylinder 7 at the bottom thereof, or below the piston head 22.

The numeral 13' designates a flexible pipe which also enters the cylinder 7, but above 45 the piston head 22.

As shown in the drawing a fluid is directed from the pipe 27 through the passage 28 of the valve and delivered through the pipe 35 to the cylinder 7, above the head 50 of the piston, and the pressure thereof sustains the piston head in its lowered position, and as a consequence the device in its rail engaging position, and the arms 13 and 14 securely located by the piston rod engaging within the slots of the fingers 17. 55 When a sufficient pressure is obtained the valve may be rotated to bring its passages 28 and 29 at registry within the ports in the valve casing, or, if desired, the cylinder 7 60 may be provided with usual bleed ports so that an excess pressure by the fluid may find an outlet.

We will now suppose that the coach or vehicle is nearing a frog or switch and it is 65 desirable to bring the device out of engage-

ment with the rail and above the heads of the rail. The valve is rotated so that its passage 29 communicates with the ports 30 and 31. This will bring the passage 28 into register with the ports 32 and 33 to allow 70 the fluid in the cylinder above the head, 22 to find an exhaust through the port 32, and will direct the fluid from the pipe 27 through the pipe 34 to below the piston head which, acting upon the outer face of 75 the said piston, will raise the same within the cylinder, causing the parts to assume the position illustrated in Fig. 2 of the drawings. It will be noted that when the device is in its lowered position, the fluid first sustained below the head 33 will find an exit 80 through its pipe 34, the passage 29 and the port 32.

In Figs. 5 to 7 I have illustrated a modified form of the device. In these figures a 85 casing 35 is supported upon the under frame of the coach or vehicle in a manner substantially similar to that hereinbefore described. The casing is substantially similar to the cylinder 4, the same having its lower and 90 open face provided with an annular in-turned bead 36, and the cylinder 37 is also substantially similar in construction to the cylinder 7, the same having its upper and closed head formed with a flange 33 which 95 may be provided with packing rings 39 so that the same will closely engage with the cylindrical bore of the casing 4. The bead 36 may comprise a removable member, and this ring has its inner face also provided 100 with packing rings 40 which frictionally engage with the outer round face of the cylinder 37. Either the bead 40 or the flange 35 may be provided with lugs 41 which will prevent the flange and bead proper contacting with each other, for a purpose which will presently be set forth. The cylinder 37 is provided with depending plates or brackets 42, substantially similar to the brackets or plates 10 of the cylinder 7, and the said 105 cylinder provides a chamber 43 which is closed at both its top and bottom. Arranged within the chamber 43 is a piston head 44 having a stem 45 which extends through a suitable packing box in the lower wall of the 115 chamber. The rod or stem 45 has its end provided with a substantially V-shaped member 46. The V-shaped member, adjacent its connection with the stem 45 is formed with a slot or opening 47 within 120 which is received the opposite ends of oppositely disposed rods 48 and 49 respectively. Each of these rods is pivotally connected as at 50 to each of the depending plates or brackets 42, and each of the said rods, beyond its pivot has a loosely connected link 51 which is secured to the tail portion of a locking dog 53. The locking dogs 53 are each pivotally connected with one of the plates 42 of the cylinder 37, and each of the 125 130

said dogs extends inwardly beyond its plate 42, the ends of the said inwardly extending portions being upset to provide engaging fingers or teeth 54. The numerals 55 designate light springs which are connected with each of the dogs 53 and with each of the plates 42, the said springs being arranged within the pivots and the engaging teeth of the dogs, to force said teeth upwardly or toward the cylinder 37. The plates 42 are provided each with a substantially rectangular opening 56, which are adapted to receive the respective upper members 57 of L-shaped arms 58. The arms have their straight or vertical portions terminating below the head of a rail 59, and it may here be stated, that, as in the device heretofore described, the present structure is arranged directly above the rail 59. The vertical members of the arms 58, have their lower ends provided with inwardly projecting axles 60 upon each of which is mounted a cone shaped antifriction roller 61 which are adapted to be disposed directly below the opposite faces of the head of the rail 59, and in close proximity therewith, but not in actual contact, and connecting the vertical members of the arms 58 and arranged above the head of the rail 59 is a contractile spring 62 which is adapted to bring the ends of the horizontal members 57 of the arms 58 into contacting engagement with each other, which engagement limits the inner movement of the roller 61, so that neither the shafts nor rollers can contact with the web of the rails. The ends of the members 57, of the arms 58 have their upper portions mounted as indicated by the numerals 63 and 64, and the apex of the substantially V-shaped member 46 is disposed directly above the said upper beveled ends of the members 57 of the arms 58. The lower faces of the members 57, at the ends of the said members are formed with lugs 65 which serve as means for preventing the arms from being removed from the plates 42 of the cylinder 37. The under-faces of the members 57 of the arms are further provided with notches or depressions 66 and 67 which are adapted to serve for the reception of the toothed ends 54 of the dogs 53 to hold the parts in the position illustrated in Fig. 5 of the drawings. Inside of the lugs 41, arranged between the bead or lip 14 and the flange 38, the cylinder 37 may be provided with a helical spring 68, as shown in Fig. 6 of the drawings, and likewise the stem 45 of the piston head 44 may be surrounded by a coiled expansion spring 69, the purpose of which arrangement will be presently set forth. The casing 35 is provided with upper and lower ports 70 and 71 respectively, each of the ports being provided with flexible pipes 72 and 73 respectively, and each of the said pipes is connected

with a valve 74, which is similar in construction to the valve illustrated in Fig. 4 of the drawings and previously described. The valve is, of course, connected with the fluid pipe which may be a branch from the main air line, and as the operation of the valve has been previously set forth in detail and as stated the structure of the valve 74 is similar to that of the valve 26, a detailed description of the operation of the valve for directing the fluid both above and below the flange or head 38 of the cylinder 37 is not deemed necessary. It will, of course, be obvious that when the fluid is directed through the pipe 73, below the head 38, the cylinder will be raised within the casing 35, and that when the fluid is directed through the pipe 72 through the port 70 above the cylinder head, the cylinder 37 will be forced in a reverse direction or downwardly of the casing 35, the cylinder may be provided with bleed ports as well as permitting for the escape of compressed fluid, as previously set forth. The chamber 43 of the cylinder 37 is also provided with ports 75 and 76, the port 75 entering above the piston head 44 and being provided with a flexible pipe 77 while the port 76 is provided with a similar flexible pipe 78, and each of these pipes leads to suitable ports in a valve 79. The valve 79 is similar to the valves 74 and 26, and, in the operation of the device, now being described, the valve 79, (assuming that the parts are in the position illustrated in Fig. 5 of the drawings,) is operated to permit of the fluid passing through the pipe 77 to within the port 75, above the piston head 44, the fluid below the piston head escaping through the pipe 78, as will readily be understood, the fluid acting upon the top of the head 44 will cause the rod or stem 45 to travel downwardly between the plates secured to the cylinder 37, the V-shaped member 76, through the arrangement of the beveled edges 63 and 64 at the upper ends of the members 57 of the arms 58, are permitted a limited downward movement before contacting between the said ends. This movement is sufficient to swing the rods 48 and 49 upon their pivots 50, to draw the rods or links 51 in an upward direction, to swing the locking dogs 53 upon their pivots, against the tension of their springs 55, to cause the teeth thereof to be withdrawn from the notches or boxes 66 and 67 in the members 57 of the arms 58. A further downward movement of the spreading member 46 will cause the arms 58 to be slid in opposite directions from the rails, against the tension of their spring 62, to bring the roller 61 out of the path of engagement with the under faces of the tread of the rail. When this is accomplished the valve 74 is operative to direct the fluid through the pipe 73 and port 71 below the

flange or head 38 of the cylinder 37, causing the cylinder to be moved upwardly within the casing 35, the compressed air previously retained within the upper portion 5 of the cylinder finding an exit through the bleed ports as well as through the pipes 7, and the port of the valve leading to the atmosphere. When the device is again to be applied for sustaining the rails against 10 accidental displacement, the arms 58 are sustained in their spread position, the compressed air is exhausted through the bleed ports and pipe 73 and directed to within the casing through the pipe 72 and port 70, 15 and the cylinder forced to its lower position. The compressed fluid is then exhausted through the port 75 and pipe 77, as well as through the bleed ports and the air is admitted through the pipe 78 and port 76 20 to below the head 44, which returns the members to the position illustrated in Fig. 5 of the drawings.

From the above description, taken in connection with the accompanying drawings, 25 the simplicity of the device as well as the advantages thereof, will, it is thought be perfectly apparent to those skilled in the art to which such inventions pertain without further detailed description.

Having thus described the invention what 30 is claimed is:—

1. In a device of the class described, a casing, a cylinder for the casing and arranged for longitudinal movement within 35 the casing, a pair of arms arranged in opposite directions and pivotally connected with the cylinder, antifrictional rollers upon the arms, a piston head within the cylinder and rod for the piston head and extending 40 below the cylinder, links connected with the arms and with the piston head, fingers connected with the arms and having over-lapping ends provided with slots, fluid means for operating the piston to force the arms together and the end of the piston rod within 45 the slots of the fingers, when operated in one direction, and to raise the piston to spread the links and to raise the rod out of engagement with the fingers.

2. In a device for preventing wheels of 50 rolling stock jumping a track, including a casing secured to the body of a vehicle and arranged above the track, a cylinder mounted for movement within the casing, a spring 55 between the cylinder and casing, the casing having a chamber and plates extending from the chamber, a pair of irregularly shaped arms having their upper portions arranged between the plates and their lower portions 60 provided with antifrictional members which are adapted to be normally sustained beneath the head of a rail to the opposite sides of a web of a rail, a piston within the chamber of a cylinder, said piston having a stem 65 extending through the same, locking means

for the arms, spreading means for the arms, a fluid pipe connection with the chamber for raising or lowering the piston, and the said locking and spreading means adapted to be actuated by the means connected with the 70 stem of the piston.

3. In a device for sustaining the wheels of rolling stock upon the rails, the combination with a vehicle, and a rail upon which the wheels of the vehicle ride, of a casing secured to the vehicle and arranged above the rail, said casing having a lower open end and provided with an inturned annular bead, a cylinder having a flanged top arranged within the casing, a flange adapted to frictionally engage with the casing and the bead of the casing adapted to frictionally engage with the cylinder, the cylinder being provided with a chamber and having plates extending below the chamber, arms 75 arranged between the plates, said arms having their ends provided with inturned axles, antifrictional members upon the axles and disposed below the head of the rail, a piston head within the chamber, said head having a stem extending through the chamber, a link loosely connected with each of the arms, said links being pivotally connected with the piston rod, the arms being formed with in-turned fingers which have their ends provided with registering slots, a pivoted connection between the links and the piston stem, the said stem adapted to be normally received within the openings in the fingers, and the piston adapted to be moved through 80 the medium of a fluid in two directions, substantially as and for the purpose set forth.

4. In a device for preventing the wheels of rolling stock leaving the rails, the combination of a vehicle and a rail for the wheels of the vehicle, of a casing connected with the vehicle and disposed above the rail, said casing having its lower open end provided with an inturned bead, and the said 90 bead having frictional rings, a cylinder having a flanged top arranged within the casing, said flange having frictional rings adapted to contact with the casing, and the frictional rings of the bead adapted to contact with the cylinder, means for preventing the bead contacting with the flange, the cylinder having a closed chamber, a piston head within the chamber, a piston rod for the head and extending below the chamber, 100 the cylinder having spaced arms disposed below the chamber, oppositely disposed irregularly shaped arms arranged between the plates and guided by the plates, means for forcing the arms toward each other and the 105 ends of the arms into contact with each other, means provided upon the arms for limiting the spreading of the arms, antifrictional rollers carried by the arms and adapted to be arranged in juxtaposition 110

with the under faces of the head of the rails, locking members for the arms, a spreading member connected with the piston and co-acting with the locking members, the chamber having upper and lower ports and flexible pipes leading from the ports, a four-way valve connected with the pipes and connected with a fluid pressure pipe, the casing being provided with upper and lower ports, the lower port being disposed between the flange of the cylinder and the bead of the

casing, flexible pipes connected with these ports, a four-way valve for these pipes, and said valve communicating with a fluid pressure pipe, all substantially as and for the 15 purpose set forth.

In testimony whereof I affix my signature in presence of two witnesses.

JOHN JOHNSON.
